VARIABLE PRESSURE HYDRAULIC CONTROL CIRCUIT FOR FLUID ACTUATED RAMS

Howard M. Purcell, Philadelphia, Pa., assignor to
H-P-M Development Corporation, Wilmington,
Del., a corporation of Delaware

Application July 8, 1947, Serial No. 759,673

4 Claims. (Cl. 60—52)

1

This invention relates to hydraulic circuits, and particularly to hydraulic circuits employing fluid intensifiers or pressure connectors of the type disclosed in the Warren R. Tucker application, Serial No. 594,413, filed May 18, 1945, now Patent No. 2,486,079, and assigned to the same assignee as the instant application.

The fluid pressure convertor disclosed in the aforementioned Tucker application is characterized by its ability to pass fluid in one direction from a fluid source at increased pressure and reduced volume and, in the opposite direction at decreased pressure and increased volume. This is accomplished by modifying the volume of the fluid passing through the convertor by a connection with exhaust which either diverts a portion of the supply of fluid to exhaust while utilizing the pressure energy thereof for compressing the remainder of the fluid to a higher pressure or, adds to the supply of fluid by fluid taken from exhaust and distributes the pressure energy in the supply of fluid throughout the entire volume of the discharged fluid.

This convertor is also characterized by being operable to discharge fluid to exhaust when both the inlet and outlet of the convertor are connected with a source of fluid.

The instant invention is concerned with an improved hydraulic circuit which utilizes all of the foregoing capabilities of the pressure convertor and by doing so a highly useful but very simple hydraulic operating circuit results. This circuit is adapted for machine tool installations, hydraulic pressing operations, and for other applications such as molding and casting presses.

Accordingly, it is a particular object of the present invention to provide an improved but simplified hydraulic operating circuit employing a fluid pressure convertor.

It is another object to provide a hydraulic operating circuit for a hydraulic motor employing a fluid pressure convertor in which the valving arrangement is very simple.

Another object of this invention is to provide a hydraulic operating circuit for a reciprocable ram in which the usual surge and pre-fill valves are eliminated through a novel arrangement of a fluid pressure convertor.

Still another object is to provide a hydraulic circuit having therein a fluid pressure convertor in which the change-over from one pressure to another is accomplished smoothly and automatically.

These and other objects and advantages will become more apparent upon reference to the

following description taken in connection with the accompanying drawing in which:

Figure 1 is a diagrammatic view of a hydraulic operating circuit according to this invention; and

Figure 2 is a diagrammatic electrical control circuit for controlling the valves of the circuit of Figure 1.

Referring to the drawing there is shown a cylinder 10 within which is reciprocably mounted the double acting ram 12 which defines with the said cylinder the ram advancing means 14 and ram retracting means 16.

The pressure for operating the ram 12 is obtained from a pump 18 which is connected to draw fluid from a reservoir 20 and which discharges the said fluid to a conduit 22.

The conduit 22 is connected by a conduit 24 with two ports of a four-way valve 26 which has therein a reciprocable valve member 28. The valve 26 also has a pair of ports connected respectively by the conduits 30 and 32 with two ports of a fluid pressure intensifier or conductor 34 of the type disclosed in the Warren R. Tucker Patent No. 2,486,079, issued Oct. 25, 1949. This intensifier also has an exhaust port connected by the conduit 36 with the reservoir 20.

In operation, when fluid is supplied to the convertor 34 through the conduit 30 a supply of fluid is delivered to the conduit 32 which is augmented by additional fluid drawn in by the convertor through the conduit 36 but at reduced pressure. Conversely, when fluid is supplied to the convertor 34 by the conduit 32 there is a supply of fluid to the conduit 30 from the convertor 34 which is reduced in volume by a predetermined amount of fluid which is by-passed from the convertor through the conduit 36 to the reservoir 20. Also, when fluid is supplied to the convertor 34 through both of the conduits 30 and 32, there is a discharge of fluid through the conduit 36 to exhaust. The discharge of fluid through the various conduits communicating with the convertor is accomplished by means of a rotary valve member, not shown, which is driven by a motor M.

The valve member 28 is arranged in the valve 26 to connect either of the conduits 30 or 32 with the conduit 24 or to connect the conduits 30 and 32 together while interrupting their communication with the conduit 24.

Communicating with the valve 26 is still another conduit 38 which leads to the advancing means 14 for the ram 12. The conduit 38 is positioned in the valve 26 between the conduits 30

and 32 and is always in communication with either one or the other or both thereof.

The valve member 28 is normally maintained in its centered, or Figure 1, position by means of the centering springs indicated at 40 and which may be of any suitable design. For shifting the valve member 28 in either direction from its centered position there are provided the pilot conduits 42 and 44 leading to opposite ends of the valve 26 and having their other ends connected with the service ports of a pilot valve 46. The pilot valve 46 also has a pressure inlet connected by conduit 48 with the discharge side of the pump 18 and exhaust ports connected by the conduit 50 with the reservoir 20. Within the pilot valve 46 is a valve member 52 which is normally held in its centered, or Figure 1, position by the centering springs S4. In its centered position, the valve member 52 connects both of the pilot conduits 42 and 44 with the pressure conduit 48. Whereupon the centering means 40 of the valve 26 will hold the valve member 28 in its centered position. Upon movement leftwardly of the valve member 52 by energization of the solenoid S1, the pilot conduit 44 is exhausted while pressure continues in the pilot conduit 42. The valve member 28 is thus urged rightwardly from its centered position. Upon de-energization of the solenoid S1 and energization of the solenoid S2 at the opposite end of the pilot valve 46, the pilot conduit 42 will be exhausted while pressure fluid will be supplied to the pilot conduit 44. This will move the valve member 28 leftwardly from its center position.

The retracting means 16 of the ram 12 is connected by a conduit 54 with one port of a valve 56 which has therein a valve member 58 normally urged by a spring 60 into position to connect the conduit 54 with the conduit 22. Upon movement downwardly of the valve member 58 by the lever 62, the conduit 54 is connected with the exhaust conduit 64. The lever 62 may be moved manually or by means of a suitable cam or projecting stud assembly, not shown, carried by the ram 12 and operable upon predetermined extension of the ram to engage the lever 62 and depress the same.

For controlling the energization of the solenoids S1 and S2 there is provided the electrical circuit shown in Figure 2. In Figure 2 there is connected between the power lines L1 and L2 the contactor coil A in series with a normally open start button 68. The start button is by-passed by the normally open blades A1 of the contactor A and the normally closed blade B2 of the contactor B. In parallel with the coil A is the solenoid S1 of the valve 46.

Also connected between the power lines L1 and L2 is a coil B which is in series with a normally open pressure switch indicated at PS which is by-passed by the normally open limit switch LS1 and the normally open blade B1 of the contactor B.

The pressure switch PS is connected with the advancing means 14 of the ram 12 while the limit switch LS1 is adapted for being actuated into its closed position by a cam 70 on the ram 12 when the latter has moved a predetermined distance in its advancing direction.

Also serially connected with the coil B is a normally closed reversing switch 72. In parallel with the coil B is a solenoid S2 of the valve 46.

Operation

In operation, let it be assumed that the pump

18 is operating, that both of the solenoids S1 and S2 are de-energized, and the ram 12 is in its retracted, or Figure 1, position.

To commence a working stroke of the ram 12 the operator closes the switch 68 thereby energizing the contactor coil A. Energization of A will close the blade A1 thereof to provide a holding circuit for the coil and also to energize the valve solenoid S1.

Energization of S1 is effective to move the valve member 52 of the valve 46 leftwardly to interconnect the pressure conduit 48 with the pilot conduit 42 while simultaneously connecting the pilot conduit 44 with the exhaust conduit 50. The supply of pressure fluid in the conduit 42 moves the valve member 28 toward its right end position and interconnects the pressure conduit 24 with the conduit 30 leading into the intensifier 34 and also interconnects the conduit 32 leading from the said intensifier with the conduit 38 leading to the ram advancing means 14.

With the valve members 28 and 52 in the aforementioned positions, the supply of fluid from the pump 18 is through the conduits 22 and 24, the valve 26 and conduit 30 to the converter 34. From the converter 34 a reduced pressure supply of fluid at increased volume is directed through the conduit 32 and valve 26 to the conduit 38. This supply of fluid acts on the ram advancing means 14 to move the ram 12 toward the right. During the rightward movement of the ram 12 the fluid expelled from the ram retracting means 16 is conducted through the conduit 54 and valve 56 to the conduit 22 where it adds to the pump discharge and augments the advancing speed of the said ram.

After the ram 12 has advanced toward the right a predetermined distance the cam 70 engages the limit switch LS1, or the pressure switch PS is actuated by pressure from the advancing means 14 thereby to energize the contactor B.

Energization of B closes the blade B1 thereof to establish a holding circuit for the coil B and to energize the valve solenoid S2. Energization of B also opens the blade B2 thereof and de-energizes the coil A which permits the blade A1 thereof to open and to de-energize the valve solenoid S1.

With the solenoid S2 energized and the solenoid S1 de-energized, the pilot conduit 42 is connected with exhaust while the pilot conduit 44 is connected with the pressure conduit 48. This brings about movement of the valve member 28 toward its left hand position which interconnects the conduits 30 and 38 and the conduits 24 and 32.

The supply of fluid from the pump 18 is now directed to the converter 34 through the conduit 32 and a reduced volume increased pressure supply of fluid is delivered from the converter 34 to the conduit 30 and thence through the valve 26 and conduit 38 to the ram advancing means 14.

The ram 12 now continues at reduced speed but under increased pressure. Should it be desired to develop a greater working thrust on the ram 12, the valve member 58 may be shifted downwardly. Actuation of the valve member 58 downwardly will operate to exhaust the ram retracting means 16.

After the work to be done by the ram 12 has been accomplished, the switch 72 may be opened by any suitable means to de-energize the coil B and the valve solenoid S2.

At this time, both of the solenoids S1 and S2 are de-energized and the valve member 52 moves to its center position under the influence of the

springs S4. As mentioned before, this places both of the pilot conduits 42 and 44 under pressure and permits the centering means 40 of the valve member 28 to move the said valve member to its center position. The conduit 38 is thus connected with both of the conduits 30 and 32 while the conduit 24 is closed off at its valve end. In order to retract the ram 12 the valve 56 is returned to its original position, if it has been moved therefrom, to interconnect the conduits 22 and 54, thus bringing about a supply of pressure fluid from the pump 18 to the ram retracting means 16. This supply of fluid urges the ram 12 leftwardly and develops a pressure in the ram advancing means 14 which is effective to pass fluid through the conduit 38, the conduits 30 and 32, and the convertor 34 to the conduit 36. The retracting movement of the ram 12 will continue until it bottoms in the cylinder 10, or until the start button 68 is again closed.

It will be noted that the circuit of this invention provides for a fast approach of the ram 12 and for two selectively available feed rates.

It will also be noted that the fast approach of the ram is obtained without the use of auxiliary booster rams and without pre-fill, surge, or unloading valves.

By employing the convertor 34 very high pressures can be developed in the ram advancing means 14 whereby high working thrusts may be exerted by a relatively small ram. By reversing the convertor in the circuit, a supply of fluid may be directed to the advancing means 14 which is sufficiently augmented to produce approach speeds comparable to these which would be obtained by an auxiliary booster ram.

It will be understood that this invention is susceptible to modification in order to adapt it to different usages and conditions and, accordingly, it is desired to comprehend such modifications within this invention as may fall within the scope of the appended claims.

I claim:

1. The combination with a fluid operable motor having a fluid pressure-receiving advancing area; of a fluid displacement pump; fluid pressure-converting means having first and second fluid inlet ports and an exhaust port and operable upon the introduction of fluid under pressure into the first inlet port to discharge fluid through the second inlet port at increased pressure and reduced volume, and upon the introduction of fluid under pressure within the second inlet port to discharge fluid through the first inlet port at decreased pressure and increased volume, said converting means being further operable in response to the simultaneous introduction of fluid under pressure within both of said inlet ports to discharge fluid through the exhaust port thereof; and valve means connected with the advancing area of said motor, said pump, and the inlet ports of said converting means and operable to selectively introduce fluid sent forth under pressure by said pump to either the first or second inlet ports of said converting means while connecting the opposite inlet port with the advancing area of said motor, or to connect both the first and second inlet ports of said connecting means with the advancing area of said motor.

2. The combination with a fluid-operable motor having advancing and retracting areas; of a fluid pressure source; a fluid pressure converter having a plurality of fluid transmission ports to receive and discharge fluid to and from convertor and a fluid outlet for exhausting fluid from said con-

vertor, said convertor being operable upon the introduction of fluid under pressure to one of its transmission ports to discharge fluid from another of its transmission ports at increased pressure and reduced volume and upon the introduction of fluid under pressure to its last-named transmission port to discharge fluid from its first-named transmission port at decreased pressure and increased volume, said convertor being further operable upon the introduction of fluid under pressure to both of its transmission ports to exhaust such fluid through its fluid outlet; a first valve means selectively operable to connect said fluid pressure source with either of the transmission ports of said convertor while connecting the other of its transmission ports with the advancing area of said motor, or to connect both of the transmission ports of said convertor simultaneously with the advancing area of said motor, and a second valve means selectively operable to connect the retracting area of said motor with said fluid pressure source or with exhaust.

3. A hydraulic control circuit for a fluid-actuated hydraulic motor having an advancing area and a retracting area, comprising a hydraulic fluid reservoir; a fluid displacement pump connected with said reservoir and operable to pump fluid under pressure therefrom; a fluid pressure and volume convertor having a reduced pressure increased volume outlet port, an increased pressure reduced volume outlet port, and an exhaust outlet communicating with said reservoir; a first valve having connections to said pump, the reduced pressure outlet port of said convertor, the increased pressure outlet port of said convertor, and the advancing area of the hydraulic motor, said first valve being operable to selectively connect either the increased pressure outlet port or the reduced pressure outlet port of said convertor with the advancing area of the motor while connecting said pump with the opposite outlet port, or to simultaneously connect both the reduced pressure port and the increased pressure port of the convertor with the advancing area of the motor, said convertor being operable in response to fluid pressure at both the reduced pressure and increased pressure ports thereof to exhaust fluid through the exhaust outlet thereof; and a second valve having connection with the retracting area of the motor, said reservoir, and said pump, said second valve being selectively operable to connect the retracting area of the motor with said reservoir or with said pump.

4. In a control circuit for a double-acting hydraulic ram having ram-advancing means and ram-retracting means, a fluid displacement pump, a fluid pressure convertor having a first transmission port, a second transmission port, and an exhaust port, said convertor being operable to receive fluid under pressure at said first transmission port and discharge the same at increased pressure from said second transmission port, or to receive fluid at said second transmission port and discharge the same at reduced pressure from said first transmission port, or to receive fluid simultaneously at both transmission ports and discharge the same through said exhaust port; and a valve connected respectively with the advancing means of the ram, said pump, and the first and second transmission ports of said convertor, said valve having a control member movable to a first position connecting said pump with the first transmission port of said convertor while connecting the advancing means of the ram with the second transmission port of said convertor, a

second position connecting said pump with the second transmission port of said convertor while connecting the advancing means of the ram with the first transmission port of said convertor, and a third position connecting both the first and second transmission ports of said convertor with the advancing means of the ram.
